PNEUMATIC THREAD REMOVER FOR LOOMS

Filed April 22, 1949

FIG.1

UNITED STATES PATENT OFFICE

2,526,269

PNEUMATIC THREAD REMOVER FOR
LOOMS

George N. Peterson, Grafton, Mass., assignor to
Crompton & Knowles Loom Works, Worcester,
Mass., a corporation of Massachusetts

Application April 22, 1949, Serial No. 89,011

7 Claims. (Cl. 139—256)

1

This invention relates to improvements in pneumatic thread removers more particularly for the thread of the outgoing bobbin incident to a weft replenishing operation of a loom and it is the general object of the invention to improve the thread pick-up means which guides the thread toward the mouth of the remover tube.

In a form of pneumatic thread remover which has gone into general use a tube is lowered from a normally raised position to place its intake mouth behind the thread on a weft replenishing beat of the loom. Extending forwardly from a point behind the intake mouth is a pick-up lip which passes under the thread to guide it toward the mouth. A strip of plush extends across the lay into which the lip is embedded when the thread remover is lowered. The thread of the outgoing bobbin lies across the plush and is moved by it toward the mouth as the lay moves rearwardly.

In the past these pick-up lips have always been made solid so that air drawn into the tube by subatmospheric pressures within it cannot move straight into the tube but must follow curved paths to enter it. As a result of these curved paths lint and dirt carried by the air is deposited at the intake mouth and soon closes the latter to prevent or impair its operation.

It is an important object of the present invention to form the lip in such manner that air may enter directly into the tube without being required to follow a curved path. In this way the lint and dirt moves along with the air into the remover tube and does not collect on the lip or around the mouth. This result may be accomplished by providing the usual form of lip with one or more openings or perforations placed so that air can move in more or less straight lines into the tube without having its velocity and dust carrying capacity reduced.

With these and other objects in view which will appear as the description proceeds, the invention resides in the combination and arrangement of parts hereinafter described and set forth.

In the accompanying drawings, wherein two forms of the invention are shown,

Fig. 1 is a side elevation of a part of a weft replenishing loom having the preferred form of the invention applied thereto, the lay, shuttle and shuttle box, and part of the loom frame being shown in section,

Fig. 2 is a plan view of the structure shown in Fig. 1,

Fig. 3 is an enlarged detailed vertical section on line 3—3, Fig. 2,

2

Fig. 4 is a front elevation looking in the direction of arrow 4, Fig. 3, the support for the pneumatic remover tube and part of the lay being shown in cross section,

5 Fig. 5 is a view similar to Fig. 4 but showing a modified form of the invention, and

Fig. 6 is a vertical section on line 6—6, Fig. 5.

Referring particularly to Figs. 1 and 2, the loom frame 10 supports a bracket 11 on which a weft 10 replenishing magazine 12 is pivoted as at 13. The bracket 11 has secured thereto a stud 14 on which a transerrer arm 15 is pivoted. The transerrer arm is normally in raised position as shown in Fig. 1, but is lowered by well known means including a bunter 16 on the lay L and a latch 17 as the lay moves forwardly on a replenishing beat.

Pivoted on the stud 14 is a carrier 20 normally in raised position but having an arm 21 which is over-hung by a stud 22 on the transerrer arm. When the latter descends stud 22 rocks the carrier 20 downwardly from the normal full line position shown in Fig. 1, and as the lay approaches its back center position after transfer 25 a rod 23 rises to return the carrier to its normal position.

A rod 25 is slideably mounted on the carrier 20 and is held yieldingly in rear position by a spring 26. The rear part of rod 25 is secured 30 to a plate 27 which supports a pneumatic thread remover tube 28. The latter is connected by a hose 29 to means creating subatmospheric pressures in the tube 28.

The lay has a shuttle box 30 to receive the 35 shuttle S from which the weft thread T extends toward the selvage of the fabric F. When the shuttle is boxed at the magazine end of the loom on a replenishing beat a cutter 31 moves rearwardly through a slot 32 in the front wall of the 40 shuttle box to cut a thread T at a point adjacent to the shuttle eye E.

When carrier 20 is rocked as described the intake mouth 35 at the bottom of tube 28 moves to a position behind the thread, see Fig. 2. The 45 lay is provided with a mass of deformable material 36, such as plush, in register with the mouth 35, and located in a well 37 in the lay. The weft thread is supported by the piles of this plush, and as the lay moves rearwardly, to the left as 50 viewed in Fig. 1, the plush moves the thread toward the mouth.

The matter thus far described is of common construction and may be made and operated as set forth for instance in prior Patents Nos. 55 2,199,296 and 2,219,768.

In carrying the preferred form of the invention into effect the tube 28 is associated with a form of pick-up lip which will avoid collection of lint and dirt at the mouth 35. To accomplish this result the lip 40 may be made as indicated in Fig. 4. The lip is preferably V-shaped and has right and left sides 41 and 42, respectively, joined by a bottom 43 which may if desired be curved. The lip may in effect be formed as an extension from the rear wall 44 of the plate 27, and has a relatively large opening 45 which is in alignment with axis of tube 28, as will be apparent from Fig. 3. The lip is not necessarily made as shown in Fig. 3, but in any event it will be on the tube 28 and move with it.

With the lip 40 made as described air can rise from a point below the lip and pass upwardly through the opening 45 and enter the mouth 35 without being required to turn a corner or follow a curved path and thus lose its ability to support lint. The mouth 35 therefore remains clear and is able to draw in enough air to remove the threads even after being in operation for a considerable length of time. As the lay moves rearwardly after a transfer operation with the lip down in the position shown in Fig. 3 the piles of the plush 38 will be deflected forwardly to leave an open space 46 under the lip 40 for the entrance of air.

In the modified form of the invention shown in Figs. 5 and 6 the lip 50, instead of having a single relatively large opening, is formed with openings or perforations 51 an arrangement of which is shown in Fig. 5, where three perforations are shown. These perforations preferably have their sides 52 parallel to the tube 28 or its axis, see Fig. 6, so that air rising from under or behind the lip will be able to pass through the perforations toward the mouth 35 with a minimum of turbulence. When fine yarns are being woven there is less likelihood that their free ends will whip into the perforations 51 than is the case with a single large opening 45. The latter, however, need not be as large as shown in Fig. 4 when very fine wefts are used.

From the foregoing it will be seen that the invention sets forth simple means by which the thread T can be directed into the mouth 35 by a forwardly extending lip having formed therein one or more air passages or perforations under the mouth, thereby enabling air to pass into the mouth 35 in more or less straight lines. The two sides 41 and 42 of the lip may conveniently be located in a plane which is transverse of and preferably though not necessarily oblique to the axis of tube 28, and the opening 45 will be large enough to permit a considerable column of air to be drawn through it into the tube 28. The lip also deflects the piles in front of it to provide a free space 46 directly under the opening 45 or perforations 51.

Having thus described the invention it will be seen that changes and modifications of the foregoing specific disclosure may be made without departing from the spirit and scope of the invention.

What is claimed as new is:

1. In a pneumatic thread remover for a thread remaining incident to a weft replenishing operation of a loom, a pneumatic tube in which subatmospheric pressures exist, and a thread pick-up

lip on the tube lying in a plane extending across the axis of the tube and provided with an opening therethrough aligned with the tube through which air can pass into the tube.

5. In a pneumatic thread remover for a thread remaining on the lay of a loom incident to a weft replenishing operation of the loom, a pneumatic tube in which subatmospheric pressures exist having a thread intake mouth moved to a position behind the thread incident to the weft replenishing operation, and a thread pick-up lip extending forwardly from a point behind the mouth under the thread and having an opening therein aligned with the tube through which air can pass into said mouth.

3. In a pneumatic thread remover for a thread remaining on the lay of a loom incident to a weft replenishing operation of the loom, a body of deformable pile material on the lay across which the thread extends, a pneumatic thread remover tube in which subatmospheric pressures exist formed with a thread intake mouth, and a thread pick-up lip on the tube extending from a point behind said mouth to a point in front thereof under said mouth and having an opening therein aligned vertically with said mouth, said lip extending into said pile material and effective due to rearward motion of the lay to deflect the piles of said material forwardly relatively to the lay to provide an open space under said opening from which air can move upwardly through said opening into said mouth.

4. In a pneumatic thread remover for a thread remaining incident to a weft replenishing operation of a loom, a pneumatic tube in which subatmospheric pressure exist, and a V-shaped thread pick-up lip on the tube having spaced sides between which is an opening aligned with the tube through which air moves into the tube due to said subatmospheric pressures.

5. In a pneumatic thread remover for a thread remaining incident to a weft replenishing operation of a loom, a pneumatic tube in which subatmospheric pressures exist having a thread intake mouth therein, and thread pick-up means on the tube having a side member at each side of the mouth extending forwardly from a point rearward of the mouth under the thread, said pick-up means having an opening between said members aligned with and under said mouth through which air is drawn upwardly into said mouth.

6. In a pneumatic thread remover for a thread remaining incident to a weft replenishing operation of a loom, a pneumatic tube in which subatmospheric pressures exist having a thread receiving mouth therein, and a thread pick-up lip on the tube extending under the mouth and having an air passage therethrough below said mouth.

7. In a pneumatic thread remover for a thread remaining incident to a weft replenishing operation of a loom, a pneumatic tube in which subatmospheric pressures exist having a thread receiving mouth therein, and a thread pick-up lip on the tube lying in a plane extending across the axis of the tube under the mouth and having a plurality of air passages therein below said mouth.

GEORGE N. PETERSON.
